RESILIENT PAD FOR USE IN CONJUNCTION
WITH HORSESHOESFrederick James Marsh, Riccarton, Christchurch,
New ZealandApplication August 9, 1937, Serial No. 158,187
In New Zealand August 18, 1936

4 Claims. (Cl. 168—28)

This invention relates to shoes for horses, more particularly race-horses and the like.

It is the object of the present invention to provide a novel and simple device adapted for

5 attachment to the hoof in conjunction with the ordinary metal shoe, and whereby a certain amount of resilience may be afforded to cushion the rear portion of the foot and frog when coming in contact with hard ground.

10 In carrying this object into effect the present invention consists briefly of a pad of suitably resilient rubber designed to underlie the rear portion of the hoof and the frog and extend across the spaces between such parts, there being embedded in the pad, in the process of its manufacture, a metal plate the two end portions of which emerge from the rubber at the lateral terminations of the latter and extend forwardly to be interlaid between the underside 15 of the hoof and the rear portions of the metal shoe and to be transfixied by the rear nails of the latter.

In order that the nature of the invention and its construction may be clearly understood, it 20 will now be fully described and explained with reference to the accompanying drawing, in which:—

Fig. 1 shows a pad in accordance with the present invention as viewed from its upper side, 30 or that which receives the foot,

Fig. 2 illustrates the underside of the pad mounted in place together with the metal shoe,

Fig. 3 is a sectional plan-view of the pad in a plane co-inciding with the upper surface of 35 the plate and illustrating a preferred form of the latter, and,

Fig. 4 is a side-view showing a hoof with the pad and metal shoe mounted thereon.

As here shown 1 is a pad of suitably resilient 40 rubber designed to underlie the rear portion of the hoof 2 and frog 3 and extend across the spaces intervening between such parts.

Embedded within the thickness of the said pad, in the process of its manufacture, is a metal 45 plate 4 the two end portions of which emerge from the rubber at the lateral terminations 5 of the latter and extend forwardly to be interlaid between the underside of the hoof 2 and the rear portions of a metal shoe 6 and to be transfixied 50 by the rear nails 7 of the latter.

In order to thus allow space for the portions of the pad underlying the rear parts of the hoof, the metal shoe 6 will terminate somewhat further from the rear than is ordinarily the case, 55 the ends 5 of the rubber from which the

extremities of the embedded plate 4 emerge being adapted to be arranged in abutment with the rear terminals of the metal shoe, as shown in Fig. 2.

The metal plate 4 is formed at its intermediate part with an enlarged portion 4a shaped to conform generally to the contour of the frog 3 which such portion is adapted to underlie.

The portions of the pad which extend between the wall of the hoof and the frog are made of increased thickness to provide at the upper side formations 1a (Fig. 1) designed to fit within the recesses which occur at such parts of the foot while at the intermediate part the upper side of the portion 4a of the plate is exposed, or covered with but a very slight film of rubber, in order to present a hard non-resilient surface to the frog.

In operation, in fitting the device, the rear portions of the metal shoe 6 underlying the extremities of the metal plate 4 will be slightly bevelled or tapered at their upper sides to form a scarf joint with the correspondingly bevelled formation of the undersides of the said parts of the plate, thus providing a true and flush surface 20 to be received against the under surface of the wall of the hoof 2 and in which condition such parts are secured by the transfixing nails 7 driven into the hoof.

By reason of the provision of the parts 1a 30 which fit within the recesses of the foot, the pad is rendered strong mechanically to withstand the severe strain imposed upon it when in use and in addition to which such parts assist materially in holding the pad securely in place. Again by 35 the provision of the hard surface presented by the upper side of the portion 4a of the plate to the frog, there will be communicated to the latter, when the horse is in action, a firm pulsating pressure which is necessary, or desirable, in 40 order to promote blood circulation of the foot.

I claim:

1. A pad for use in conjunction with a metal horseshoe, comprising a pad of suitably resilient rubber designed to underlie the rear portion of the hoof and the frog and terminating laterally in edges adapted for abutment with the rear terminals of said shoe, a metal plate embedded in said pad, the two extremities of said plate emerging from the rubber at said lateral terminations and being adapted to be interlaid between the underside of the hoof and the rear portions of said shoe and to be transfixied by the rear nails of the latter.

2. A pad for use in conjunction with a metal 55

horseshoe as defined in claim 1, characterized in that the rubber is of increased thickness at the portions extending between the wall of the hoof and the frog to provide at the upper side of said pad formations designed to fit within the recesses occurring at said parts of the foot.

3. A pad for use in conjunction with a metal horseshoe as defined in claim 1, characterized in that at the part underlying the frog the material of the pad on the upper side of said plate

is reduced in thickness to provide a hard surface in contact with said frog.

4. A pad for use in conjunction with a metal horseshoe, as defined in claim 1, characterized in that said plate at its intermediate part is formed with an enlarged portion shaped to conform generally to the contour of the frog which such portion is adapted to underlie. 5

FREDERICK JAMES MARSH. 10
